[57] CLAIM

The ornamental design for a handle, as shown and described.

DESCRIPTION

FIG. 1 is a perspective view of a handle showing my new design;

FIG. 2 is an enlarged top plan view of the handle of FIG. 1; FIG. 3 is an enlarged right side elevational view of the handle of FIG. 1, the left side elevational view of the handle being a mirror image thereof;

FIG. 4 is an enlarged front end elevational view of the handle of FIG. 1; and,

FIG. 5 is an enlarged rear end elevational view of the handle of FIG. 1.

The broken line showing of a container in FIG. 1 is for illustrative purposes only and forms no part of the claimed design.
